UNITED STATES PATENT OFFICE

HERBERT D. BROWN AND CAMIL A. SABBAH, OF SCHENECTADY, NEW YORK, ASSIGNEES
TO GENERAL ELECTRIC COMPANY, A CORPORATION OF NEW YORK

SPACE DISCHARGE DEVICE

Application filed December 15, 1926. Serial No. 155,045.

Our invention relates to space discharge devices comprising an anode arranged to transmit current in one direction through a circuit including a cathode, and has for its principal object the provision of an improved anode structure whereby destructive arcs during the operation of such a device are prevented.

One of the most serious difficulties encountered in the operation of space discharge devices, such as a mercury rectifier comprising a cathode and one or more anodes, is the formation of destructive arcs either between a negatively charged anode and the cathode or between different anodes. Such arcs may be caused by pockets of comparatively high vapor pressure produced within the highly evacuated vessel at the surface of an anode, either by volatilization of the anode material or by the volatilization of mercury which is condensed in the upper part of the evacuated vessel and drops or runs down on the hot surfaces of the anodes.

Volatilization of the anode material is objectionable not only because of the destructive arcs which it tends to produce but also because of the fact that it is deposited as a conducting film on the inner surfaces of the insulators interposed between the cathode and anodes. One cause of overheating and volatilization of the anodes seems to be the tendency of the current to concentrate at one spot on the anode surface. The reasons for this tendency are not well understood. It is known, however, that such concentration of the current can persist only as long as the affected spot is located in an electrostatic field and has a higher conductivity and positive ion density than the remaining areas of the anode. In order to ensure proper current distribution over the active area of the anode we locate this area in a weak electrostatic field and give it such a contour that the stream of atoms, positive ions and electrons emanating from the concentration area will produce a rise in the conductivity of another part of the active area. Under these conditions a concentration of current at one spot of this active surface automatically increases the current at another spot on this surface and

diverts the current from the affected spot to another part of the surface.

In accordance with our invention, these various difficulties are avoided by the provision of an anode which is so constructed that only its active surface is exposed to the interior of the evacuated chamber and that this surface is opposed to itself at different points and located in a very weak electrostatic field.

Our invention will be better understood from the following description when considered in connection with the accompanying drawings and its scope will be pointed out in the appended claims.

Referring to the drawings, Fig. 1 shows a transverse section of a rectifier wherein our invention has been embodied; Fig. 2 shows a section of an anode constructed in accordance with our invention; Figs. 3, 4 and 5 show various details in a modified form of anode; and Fig. 6 shows a further modification in the anode structure.

Fig. 1 shows a rectifier comprising an evacuated vessel 1 which is surrounded by a cooling chamber 2 and contains a mercury cathode 3, an anode connected to a lead 4 and a starting electrode 5. It will be observed that the tank 1 is insulated from the cathode 3 by means comprising an insulator 6, from the anode lead 4 by means comprising insulators 7 and 8, and from the starting electrode 5 by means comprising an insulator 9. Aside from the structure of the anode, the various illustrated features of the rectifier are well understood by those skilled in the art and need not be described in further detail.

As shown more clearly by Fig. 2, the anode structure comprises a cylindrical anode 10 which is connected at its upper end through a hollow stem 11 to the lead 4 and is welded at its lower end to a cylindrical member 12. This member is provided with a flange 13 and is closed at its upper end so as to form an annular chamber which surrounds the anode 10 and the stem 11 and is interconnected with the interior of this stem through ducts 14 in the upper end of the anode. Pipes 15 and 16 are arranged to permit the circulation of

a cooling medium through the member 12 and the stem 11.

The member 12 is supported at the upper end of an extension 17 of the vessel 1 through means comprising the insulator 8 and a member 18 provided with a flange 19 at its upper end and with a flange 20 at a point intermediate its ends. A sealed joint between the flange 20 and the upper end of the extension 17 is produced by means of a split ring 21 and bolts 22. The flanges 13 and 19 are clamped to the upper and lower surfaces of the insulator 8 by means comprising rings 23 and 24, bolts 25, a gasket 26 and the insulator 7. Under these conditions, vacuum tight seals are produced at the upper end of the extension 17 and at the upper and lower surfaces of the insulator 8.

In order to restrict the active area of the anode to a part of the surface located in a weak electrostatic field and to protect the interior surface of the insulator 8 from volatilized material which would tend to produce a conductive film on its inner surface, an insulation shield 27 of alumina, or the like, is suspended from the insulator 8 in a manner to cover the part of the member 18 located within the vessel 1 and to cover the interior surface of the anode 10 at its lower end. An insulation washer 28 and a funnel-shaped member 29 are supported upon the lower end of the member 18 and held in contact with the lower end of the shield 27 by suitable means shown as screws 30.

It will be apparent that this structure not only limits the active surface of the anode to an area where the electrostatic field is substantially zero and shields the insulator surface from the vaporized material of the anode, but also shields the hot surface of the anode from condensed mercury.

The length of the interior anode surface that should be covered by the insulation shield 27 is dependent on the internal diameter of the anode. In order to ensure that the electrostatic field at the active surface of the anode is substantially zero, it is essential that the insulation shield extend up into the anode a distance which is of the same order as the internal diameter of the electrode. Under these conditions the electrostatic lines of force produced at opposed points on the active surface tend to neutralize each other and the danger of concentration of current at one spot of the anode surface is avoided due both to the fact that any electrons emitted from the active surface of the anode are in a very weak electrostatic field and to the further fact that any stream of positive ions produced by these electrons is projected into an opposed area of this surface thereby increasing the conductivity of this opposed area and preventing further concentration of the current at the affected spot.

The anode structure illustrated by Figs. 3,

4 and 5 differs from that illustrated by Fig. 2 in that it comprises an anode 31 provided with a plurality of recesses 32 in its lower end and with cooling ducts 33 which are located between the recesses 32 and extend between the upper and lower ends of the anode. In order to confine the arc to a part of the anode surface where the electrostatic field is substantially zero, the insulation shield is extended up into the recesses 32 far enough to cover the part of the surface where the electrostatic lines of flux do not neutralize each other.

Fig. 6 shows an anode structure comprising an external anode 34 provided with a flange 35 which is clamped between an insulator 36 and an insulator 37 in a manner to form a vacuum tight joint at the lower surface of the flange. In this structure, an insulation shield 38 supported on the insulator 37 is arranged to extend into the anode chamber far enough to confine the arc to a part of the anode surface where the electrostatic field is substantially zero and into the evacuated chamber far enough to protect the interior surface of the insulator 37 from volatilized anode material. The other details of this structure will be readily understood in view of what has been said with respect to the previous figures.

The embodiments of the invention illustrated and described herein have been selected for the purpose of clearly setting forth the principles involved. It will be apparent, however, that the invention is susceptible of being modified to meet the different conditions encountered in its use and we therefore aim to cover by the appended claims all modifications within the true spirit and scope of our invention.

What we claim as new and desire to secure by Letters Patent of the United States, is—

1. A mercury arc device comprising an evacuated vessel, a cathode, an anode having a recess formed therein and provided with an active surface and an inactive surface, said active surface and a portion of said inactive surface being formed by the surfaces of said recess, and an insulation shield mounted within said vessel and extending into said recess of said anode a distance at least as great as the width of said recess to cover said portion of said inactive surface within said recess.

2. A mercury arc device comprising an evacuated vessel, a cathode, a hollow insulator, an anode supported on said insulator and provided with a cylindrical recess in one of its surfaces, said anode being provided with an active surface and an inactive surface, said active surface and a portion of said inactive surface being formed by the walls of said recess, and an insulation shield extending into said recess a distance at least as great as the diameter of said recess to cover said por-

tion of said inactive surface within said recess and extending over the interior surface of said hollow insulator.

3. A mercury arc device comprising an evacuated vessel, a cathode, an anode having a cylindrical recessed surface and provided with an active surface and an inactive surface, said active surface and a portion of said inactive surface being formed by said cylindrical recessed surface of said anode, a hollow insulator interposed between said cathode and said anode, and an insulation shield mounted within said vessel to cover the interior surface of said insulator, said shield extending into said anode a distance at least as great as the internal diameter of said anode recess to cover said portion of said inactive surface within said anode.

In witness whereof, the said HERBERT D. BROWN has hereunto set his hand this 14th day of December, 1926, and the said CAMIL A. SABBAH has hereunto set his hand this 2nd day of December, 1926.

HERBERT D. BROWN.
CAMIL A. SABBAH.
